UNITED STATES PATENT OFFICE.

CAROL BONWIT AND LESTER R. BONWIT, OF BALTIMORE, MARYLAND.

DESIGN FOR A DOLL.

54,495.

Specification for Design. Patented Feb. 17, 1920.

Application filed April 5, 1919. Serial No. 287,912. Term of patent 3½ years.

To all whom it may concern:

Be it known that we, CAROL BONWIT and LESTER R. BONWIT, citizens of the United States, and residents of the city of Baltimore, in the State of Maryland, have invented a new, original, and ornamental Design for Dolls, of which the following is a specification, reference being had to the accompanying drawing, forming part thereof.

Fig. 2 is a side perspective view of the same.

We claim:

The ornamental design for a doll, as shown.

CAROL BONWIT.
LESTER R. BONWIT.
